UNITED STATES PATENT OFFICE.

MATHIAS ODIN SEVERIN MADSEN, OF AARHUS, DENMARK, ASSIGNOR TO OTTO KRISTIAN HEESCH, OF AARHUS, DENMARK.

AUTOMATIC ELECTRIC METER.

Application filed November 4, 1922. Serial No. 599,133.

To all whom it may concern:

Be it known that I, MATHIAS ODIN SEVERIN MADSEN, subject of the King of Denmark, residing at Aarhus, Denmark, have 5 invented certain new and useful Improvement in Automatic Electric Meters (for which I have filed application in Denmark Aug. 27, 1921; in Germany Sept. 6, 1921; and in Great Britain Oct. 3, 1921), of which

10 the following is a specification. *

The present invention relates to an automatic mechanism adapted to be fitted into or constructed in one with an electric meter of any kind, which mechanism, after a coin 15 of a predetermined value has been inserted, can be set in such a manner that it allows of an amount of electricity corresponding to the sum thus paid in passing through the respective electric meter, whereupon the mechanism 20 will automatically interrupt the passage of current through the meter. The said setting can be repeated once or several times successively up to a given maximum number of times, so that either one coin only, or 25 several may be paid in, one immediately after the other.

At each setting of the mechanism, which is rendered possible by the insertion of a coin, a member which effects the closing and 30 the opening of the circuit, is shifted a certain distance away from the position in which it effects the opening of the circuit, and when the meter is in operation, it will, in a suitable manner, move the said member 35 in a direction opposite to that in which it had been previously shifted. The time, during which electricity can be dispensed for the sum of money corresponding to the coin inserted, is thus directly in proportion to 40 the length of the distance through which the said member can be shifted after the insertion of a coin. The automatic mechanism is, in known manner, arranged so that this shifting can be regulated within wide limits, 45 so that the electric automaton can at any time be regulated to correspond to the rates of charge for electric current existing at the time.

In the accompanying drawing a constructional form of the invention is shown, in which:—

Figure 1 is a front view of the automatic mechanism with the various parts in

the positions in which they will be when the passage of current through the electric 55 meter cannot take place.

Figure 2 is a side view thereof, and Figure 3 is a front view, showing the mechanism in the position for the passage of current, the disc containing the insertion 60 slot and a setting disc attached to same being removed.

The automatic mechanism consists of a disc 1, Figure 1 with a coin insertion slot 2, a setting disc 3 disposed within the said disc, and a combined ratchet and carrier wheel 4, which contains a plurality of radial coin channels 5 which extend up to the periphery of the wheel; said parts are already known and shall, therefore, not be 65 here discussed any further. It may only be mentioned that a coin inserted will couple the setting disc 3, which is fitted on a stud 6 passing centrally through disc 1, and on the outside thereof having a handle 7, with the ratchet and carrier wheel 4, and that thereupon, by means of the handle 7, the disc 3 and wheel 4 can be turned through 70 a central angle in the direction of the arrow in Figure 1. As soon as this turning ceases, 75 the coin will drop down into a coin container, whereupon the setting disc 3, as soon as the handle 7 is released, will, under action of a spring, be returned into its 80 normal position, whilst the returning of the 85 wheel 4 is prevented by a pawl 8.

In a suitable, fixed holder is revolvably, but not shiftably fitted a nut 9, Figure 2, on the one end of which is formed or fitted a bevel gear 10 which meshes with a bevel gear 11, Figure 3, on a shaft 12, which is by suitable means, driven by the works of the meter not shown, when the meter is in operation. Through the nut 9 is screwed 90 a shaft 13 having a screw thread on a part 95 of its length, which shaft is coaxially disposed with the stud 6, and that part of said shaft which is in Figure 2 to the right of the threaded part, is of a square section and carries the ratchet and carrier wheel 4, 100 through which the shaft passes shiftably (but, owing to its square section, not revolvably). The shaft is therefore turned together with the wheel 4, when the latter is in the aforescribed manner turned, by aid 105 of a coin inserted, through a given angle,

and as the nut 9 is held or locked by the bevel gearing 10, 11 whilst the said turning of wheel 4 takes place, and works of the meter are not operating, the result will be 5 that the shaft 13 is axially shifted, the length of this axial displacement being in proportion to the angle through which the wheel 4 is turned. This shifting of shaft 13 will be in a direction to the right in Figure 2. 10 When, on the other hand, the meter is in operation, this movement will, by means of the shaft 12 and the bevel gearing 11, 10 be transmitted to the nut 9, whilst the turning of shaft 13 is prevented by the pawl 8 holding back wheel 4. The consequence is that 15 the shaft 13 receives an axial motion which, however, proceeds in a direction opposite to the direction of the previous axial movement, i. e. to the left in Figure 2. It is 20 these axial movements which are here utilized for the object in view.

Into the path of the coin in one of the coin slots there extends (when the mechanism has opened the circuit of the meter) 25 the slanting outer end of an arm 14, Figure 1 which is fixed on a revoluble shaft 15, Figure 2, on which is also fixed another, bent arm 16. The outer end of the latter bears against a pin 17, which is secured eccentrically in the one end of a revoluble contact cylinder 18, on the periphery of which is disposed a contact piece 19 to contact with a contact spring 20. The cylinder 18 is under influence of a coiled spring (torsional 30 spring) 21, which tends to hold it in the position shown in Figure 1, in which the contact spring is not in contact with the contact piece so that the circuit of the meter is open, whilst the pin 17, by its action 35 on arm 16, will hold the shaft 15 turned so that the slanting outer end of arm 14 extends into the path of the coin. If, now, after a coin has been inserted through the slot 2, the combined ratchet and carrier 40 wheel 4 is turned, the coin, which is now in one of the slots 5 of said wheel, will abut against the slanting end of arm 14 and turn the shaft 15 and with the latter also the arm 16 in such a manner, that the last named 45 arm, by pressing on the pin 17, will turn the contact cylinder 18 into the position shown in Figure 3 with the contact piece 19 in contact with the contact spring 20, and as soon as the cylinder has reached this 50 position, the one end of a double-armed lever 22 under action of a spring 27 will engage in a notch 23 in a flange 24 on said cylinder, whereby the cylinder is locked. The respective consumer may now obtain current 55 through the meter.

The other end of the lever 22 forms an abutment 25 which may project into the path of the shaft 13. The end 26 of shaft 13, see 60 Figure 2, is moved away from said abutment 25 when the said shaft 13 is turned

together with wheel 4 through the available angle by means of the handle 7 and under co-operation of the coin inserted.

If thereupon another coin is inserted, the end 26 of the shaft 13 may be removed by 70 the same distance further from the abutment 25, whilst the contact cylinder remains in its effective position, and so on, until the shaft 13 cannot be shifted any further to the right (Figure 2). 75

After the electric meter has in the afore-described manner been brought into an operative condition by the setting of the automatic mechanism, which has been rendered possible by the insertion of one or several 80 coins, current can be supplied until the amount of current consumed has, by passing through the meter, caused the meter works to turn the nut 9 and thus shift the shaft 13 so far to the left (Figure 2) that the end 26 of said shaft 13 will by abutting against the abutment 25 turn the lever 22 out of engagement with the notch 23 in the flange 24 of the cylinder 18. As soon as this takes place, the spring 21 will turn the contact 90 cylinder 18 into the position shown in Figure 1, in which the contact piece 19 is out of contact with the contact spring 20. The meter circuit is then opened and can only be closed again by a coin being inserted into 95 the automaton and the wheel 4 being thereupon turned.

As the operation of the automatic mechanism is apparent from the foregoing description, said operation need only be briefly explained. After a coin has been inserted, the wheel 4 is, by means of the handle 7 turned in the direction of the arrow in Figure 1 through such an angle as the mechanism will allow. This turning of wheel 4 has 100 the effect that the end of the shaft 13 is removed by a certain distance from the abutment 25 on the one end of lever 22, and during the latter part of this turning the coin will abut against the arm 14, whereby 105 the arm 15 and with it arm 16 is turned in such a manner, that the latter arm turns the contact cylinder 18 into operative position, Figure 3. The meter is now in operative position and the contact cylinder is 110 locked by the lever 22 engaging in the notch 23 until the end 26 of shaft 13, in consequence of the axial movement which said shaft 13 receives by the working of the meter mechanism, releases the lever from the 115 notch 23 by pressing against the abutment 25. As soon as this takes place, the contact cylinder is turned under action of the spring 21 into its inoperative position, Figure 1. The amount of electricity which can be 120 obtained for a coin of a given value is thus determined by the fact that the meter, through which said electricity must pass, and which by its consequent operation will 125 shift the shaft 13, will allow of a passage of 130

current only until said shifting has reached a predetermined value.

Said value may, in known manner, be regulated by the disc 1 being adjusted into such a position, that the coin slot 2 will be located at a greater or lesser angle from the position which the coin inserted assumes when the wheel 4, which receives the coin, has been turned into its terminal position.

10 I claim:

1. Stop mechanism for an electric meter having coin controlled mechanism of the type described, comprising a rotary cylinder, a spring for rotating the cylinder in one direction, a contact piece on the cylinder, a contact member capable of engaging said contact piece when the cylinder is in one position and the circuit is closed, and coin controlled means for moving the cylinder to bring the contact members into engagement with each other comprising a shaft, an arm secured to the shaft and capable of extending into the path of the coin in the coin controlled mechanism, a second arm fixed on the same shaft, and a projection on the end of the cylinder and extending into the path of the said second arm, so that the said spring acting upon the cylinder holds the first mentioned arm in the path of the coin when the contacts are out of engagement, and the movement of the coin operates the said arms and projection to bring the contacts into engagement with each other.
2. Stop mechanism for an electric meter having coin controlled mechanism of the type described, comprising a rotary cylinder, a spring for rotating the cylinder in one direction, a contact piece on the periphery of the cylinder, a spring carrying a contact member for engaging the contact piece on the cylinder when the circuit is closed and the cylinder is held in one position, and coin controlled means for moving the cylinder to bring the contact members into engagement with each other comprising a rocking shaft, an arm secured to the shaft and capable of extending into the path of the coin in the coin controlled mechanism and having a slanting outer end for engagement with the coin, a bent arm fixed on the same shaft and a pin projecting outwards from the end of the cylinder and located in the path of the extreme outer end of the bent arm, so that the said spring acting upon the cylinder holds the slanting end of the first mentioned arm in the path of the coin when the contacts are out of engagement, and the movement of the coin operates the said arms and projecting pin to bring the said contacts into engagement with each other.
3. Stop mechanism for an electric meter having coin controlled mechanism of the type described, comprising a rotary cylinder, a spring for rotating the cylinder in one direction, a contact piece on the periphery of the cylinder, a spring carrying a contact member for engaging the contact piece on the cylinder when the circuit is closed and the cylinder is held in one position, and coin controlled means for moving the cylinder to bring the contact members into engagement with each other comprising a shaft, an arm secured to the shaft and capable of extending into the path of the coin in the coin controlled mechanism, a second arm fixed on the same shaft, and a projection on the end of the cylinder and extending into the path of the said second arm, so that the said spring acting upon the cylinder holds the first mentioned arm in the path of the coin when the contacts are out of engagement, and the movement of the coin operates the said arms and projection to bring the contacts into engagement with each other.

ble of extending into the path of the coin in the coin controlled mechanism, a second arm fixed on the same shaft, and a projection on the end of the cylinder and extending into the path of the said second arm, so that the said spring acting upon the cylinder holds the first mentioned arm in the path of the coin when the contacts are out of engagement, and the movement of the coin operates the said arms and projection to bring the contacts into engagement with each other.

3. Stop mechanism for an electric meter having coin controlled mechanism of the type described, comprising a rotary cylinder, a spring for rotating the cylinder in one direction, a contact piece on the periphery of the cylinder, a spring carrying a contact member for engaging the contact piece on the cylinder when the circuit is closed and the cylinder is held in one position, and coin controlled means for moving the cylinder to bring the contact members into engagement with each other comprising a rocking shaft, an arm secured to the shaft and capable of extending into the path of the coin in the coin controlled mechanism and having a slanting outer end for engagement with the coin, a bent arm fixed on the same shaft and a pin projecting outwards from the end of the cylinder and located in the path of the extreme outer end of the bent arm, so that the said spring acting upon the cylinder holds the slanting end of the first mentioned arm in the path of the coin when the contacts are out of engagement, and the movement of the coin operates the said arms and projecting pin to bring the said contacts into engagement with each other.

In testimony whereof I affix my signature in presence of two witnesses.

MATHIAS ODIN SEVERIN MADSEN.
